SOFA

Forest Wilson, Chicago, Ill.

Application June 28, 1954, Serial No. 31,210

Term of patent 14 years

(Cl. D15—11)

To all whom it may concern:

Be it known that I, Forest Wilson, a citizen of the United States, residing at Chicago, county of Cook and State of Illinois, have invented a new, original, and ornamental Design for a Sofa, of which the following is a specification, reference being had to the accompanying drawing which forms a part thereof.

Figure 1 is a perspective view of a sofa embodying my design; Figs. 2, 3, 4, and 5 are respectively plan, front elevation, and end elevation views of the sofa of Fig. 1.

I claim:

The ornamental design for a sofa, as shown.
